UNITED STATES PATENT OFFICE.

LE GRAND PARISH, OF MOUNTAINVIEW, NEW JERSEY, ASSIGNOR TO AMERICAN ARCH COMPANY, OF NEW YORK, N. Y., A CORPORATION OF DELAWARE.

LOCOMOTIVE-FIRE-BOX ARCH.

1,229,378.

Specification of Letters Patent. Patented June 12, 1917.

Application filed January 8, 1916. Serial No. 71,061.

To all whom it may concern:

Be it known that I, LE GRAND PARISH, a citizen of the United States, and a resident of Mountainview, Passaic county, New Jersey, have invented certain new and useful Improvements in Locomotive-Fire-Box Arches, of which the following is a specification.

My invention relates to improvements in refractory arches or baffles for locomotive boiler furnaces and has special reference to improvements in the mounting of refractory arch bricks upon the water-circulating arch tubes of such boilers.

The material of which arch bricks are made is highly abrasive; so much so, that as the metal arch tubes expand, contract and warp during usage, the coincident movement of the refractory bricks upon the arch tubes wears away the portions of the tubes upon which the bricks rest. Not infrequently arch tubes are allowed to remain in the fireboxes until from these causes they are worn so thin as to burst under boiler pressure or collapse under the weight of the arch bricks. Doubtless the danger could be avoided by frequent inspection and replacement of the tubes; but the difficulty is that the tubes cannot be inspected without removing the arch bricks, and the amount of time and labor needed for that operation is such that it has become the practice to postpone inspection of the tops of the arch tubes until the time of the removal of the bricks or until some clearly apparent fault in an arch tube makes the operation necessary.

The objects of my invention are, to avoid these dangers;—to make the frequent inspection of arch tubes unnecessary;—to avoid the heavy expense of tube replacements due to the arch brick wear;—and to prolong the life of arch tubes.

I accomplish these objects by interposing a relatively permanent, but easily removable, wearing strip between each arch tube and every brick which rests upon it. I prefer that the wearing strips shall be composed of an asbestosoid substance, capable of long withstanding the wear of the bricks, and that the strips shall be held in place upon the tubes by means of a cement adapted to withstand the high temperatures of the firebox.

My invention will be readily understood on reference to the accompanying drawings that form part of this specification, and in which: Figure 1 is a vertical cross-section of a locomotive firebox containing a front arch embodying my invention:—Fig. 2 is a detailed view of the arch in a plane perpendicular to the inclined arch tubes;—Fig. 3 is a perspective detail still better illustrating the tube protecting or wearing strips;—Fig. 4 is a longitudinal view of a tube and its wearing strip;—and, Fig. 5 is an enlarged cross section thereof.

In Fig. 1 of the drawings, 2 represents the flue sheet of a locomotive boiler furnace or firebox. Typical side sheets, 3, 3, 70 and a typical crown sheet, 4, are shown. The forwardly and downwardly inclined water-circulating metal arch tubes, 5, may be of any desired number, shape and size. They are usually spaced at equal distances 75 and ordinarily are parallel. The marginal arch bricks, 6, are supported by the outer tubes, 5, and the side sheets of the firebox. Intermediate arch bricks, 7, close the spaces between the several arch tubes. The wearing 80 or protecting strips marked, A, are placed on the tops of the tubes and the several bricks rest thereon instead of directly upon the tubes. As best shown, in Fig. 2, the arch bricks are of the sectional type, characterized by socketed ends, 8, shaped to fit the arch tubes. In many instances the bricks will be found to be of the kind shown in Fig. 3, that is, characterized by an inclined end, 9, formed to slide upon or 85 against the supporting tube. Bricks of this character have but little movement on the tube at their socketed end, 8', and the movement of the inclined end, 9, against the arch tube is proportionally exaggerated. In the case of bricks which are socketed at both ends, as shown in Fig. 2, the wear upon the tubes is practically equally divided. In the case of bricks having inclined ends, 9, the principal wear occurs at the tube against 90 which the inclined tube rests. In either case I protect the top and sides of the tube by applying thereto a strip, A. This strip is curved to conform to the tube and, as shown, protects all parts of the tube which 95 is likely to receive the wear of variously formed arch bricks. It will be noted that the bricks are arranged end to end in

several horizontal rows. Each tube carries the ends of two bricks in the same horizontal row, as best shown in Fig. 3.

I prefer to fasten the wearing strips in place upon the tubes so that they shall not be dislodged in assembling the parts, or by relative movement of the bricks and tubes due to changes of temperature in the firebox. Obviously, the wearing strips support the 10 bricks and take the wear thereof, thus relieving the metal tubes, 5, which it is important to preserve.

I have obtained the best results by employing asbestos wearing strips, of a thickness approximating the thickness of the 15 walls of the arch tubes. Such material is a closely compacted, somewhat fibrous composition, and long resists the wear of the rough contacting surfaces of the bricks. My 20 further purpose in employing strips of such material will be apparent on observing that in the first wearing movements of the brick a portion of the asbestos material is worn away and is in considerable part retained, 25 as a filler by the rough surface of the brick. In this manner the contacting surface of the brick is provided with a smoother surface, chiefly composed of the same material as the strip; and thereby the body portion of the 30 wearing strip is largely relieved from the cutting effect of the abrasive brick surface. In Fig. 5, I have attempted to depict the manner in which the rough surface of the brick-end is thus filled and made relatively

smooth by the gradual taking of material 35 from the body of the wearing strip.

In first placing the strips upon the tubes I coat them with a suitable adhesive cement adapted to quite strongly attach the asbestos material to the metal surface of the 40 tube and also adapted to resist decomposition at the temperatures attained by the water filled arch tubes. I have not found it necessary to devise any new asbestos material or any new cement, as several kinds of 45 each may be obtained in the open market under various commercial names.

Having thus described my invention, I claim as new and desire to secure by Letters Patent:—

1. A locomotive firebox and contained group of water-circulating arch tubes, in combination with refractory arch bricks supported by and between said tubes, and thin wearing strips of initially pliable, non-metallic refractory material interposed between said tubes and bricks. 50

2. A locomotive firebox and contained group of water-circulating arch tubes, in combination with refractory arch bricks 60 supported by and between said tubes, and thin initially pliable wearing strips composed of material differing from both bricks and tubes, and adhesively attached to the tubes to receive the wear of the bricks. 65

In testimony whereof, I have hereunto set my hand this 28th day of December, 1915.

LE GRAND PARISH.
